UNITED STATES PATENT OFFICE.

BARNES CLAYTON, OF PHILADELPHIA, PENNSYLVANIA.

SPRING-MOTOR.

SPECIFICATION forming part of Letters Patent No. 309,524, dated December 23, 1884.

Application filed May 31, 1884. (No model.)

To all whom it may concern:

Be it known that I, BARNES CLAYTON, of the city and county of Philadelphia, and State of Pennsylvania, have made new and useful 5 Improvements in Spring-Motors, of which the following is a specification.

My invention has reference to spring-motors; and it consists in certain improvements fully set forth in the following specification, 10 and shown in the accompanying drawings, which form part thereof.

Heretofore it has been customary to make spring-motors with spiral or coiled springs; but in large motors great difficulty has been 15 experienced in securing a strong spring combined with durability, and the expense is very great.

The object of my invention is to construct a simple, durable, and inexpensive motor in 20 which the springs are formed of thin flat blades laid one upon another in the manner commonly seen in carriage-springs.

In the drawings, Figure 1 is a side elevation of a spring-motor embodying my improvements. Fig. 2 is a sectional plan view of same on line *x x*, and Fig. 3 is a side elevation of a modified form thereof.

A is a frame of any suitable construction. *B* *B'* are two sets of springs, formed of thin flat 30 blades, the upper ones of which become shorter and shorter until close to the supports or bases *b*, so that the free ends *b'* can be drawn up, causing the spring to assume the curve of a spiral, as indicated in dotted lines. To 35 make the motor compact, I place these springs close to the bottom of frame *A*, and arrange the springs of the two sets alternately, as shown in Fig. 2. These springs are simple in construction, cheap to make, and most durable 40 in their elasticity. They can be made of any strength required, and while their movement is small, they can be geared up so as to cause the motor to run for a long period before it is necessary to rewind. The ends of 45 these springs are connected by bands or chains *F* to the drums *D* *D'*, which are provided with the square heads *E*, upon which to apply the key to wind them up. These drums are connected with the spur-wheels *C* *C'* by pawl-and-

50 ratchet devices *d*, as is customary in spring-motors, to allow of their being wound up

without disturbing the gearing. These spur-wheels are arranged to drive the speed-gearing *G* by means of pinions *I*, *J*, and *K*.

H is the band-wheel by which the power is 55 applied to the sewing-machine or other mechanism to be set in motion, or the gearing may connect direct therewith.

The pinion *J* is carried by a lever, *L*, having the center of pinion *I* for a fulcrum, and 60 may be set and secured by a locking-segment, *M*.

Pivoted on the arm *L* and center of pinion *J* as a fulcrum is a bell-crank lever, *N*, which may be secured in one of three positions by a 65 segment, *P*, carried by arm *L*. The free arm of bell-crank *N* carries the pinion *K*, which is adapted to mesh with the spur-wheels *C* *C'*, and the three pinions *I*, *J*, and *K* mesh with each other at all times. In the position 70 shown the drum *D'* is driving the gearing *G*. To make drum *D* do this work, it is simply necessary to shift the lever *N*, when the pinion *K* will be thrown out of contact with spur-wheel *C'* and into contact with spur-wheel *C*, 75 moving about pinion *J* as a center. Now, to make both drums drive the gear, it is simply necessary to shift the arm *N* to the middle position, and then depress lever *L* until the pinion *K* is meshing with both the spur-wheels *C* and *C'*, which rotate in the same 80 direction.

If desired, a series of springs may be arranged one above the other, to multiply the power of the motor.

In place of the springs having one end rigid, I may make them double, as shown in Fig. 3, in which these springs *B* are made up of leaves, as before, but are secured to the supporting-rod *R* at their middle points, and the free 90 flexible ends are connected by chains or bands to the drums, as before. In place of a single spring a series of them may be arranged parallel to each other and connected together, as shown.

While I prefer the construction shown I do not limit myself thereto, as the details may be modified in various ways without departing from my invention.

Having now described my invention, what I 100 claim as new, and desire to secure by Letters Patent, is—

1. A spring-motor having the springs therein formed of a series of thin straight plates, and having one of their ends securely held and the other free, and secured to the actuating cord, band, or chain, substantially as and for the purpose specified.

2. In a spring-motor, the combination of a spring consisting of a series of flat plates rigidly secured at one end with a drum, a band or chain connecting said drum with the free end of said spring, and speed-gearing arranged to be driven by the rotation of said drum, substantially as and for the purpose specified.

3. In a spring-motor, two sets of springs formed of flat plates rigidly secured at one end, in combination with two drums, speed-gearing, and means, substantially as set forth, for putting the said speed-gearing into action by either of said drums, substantially as and for the purpose specified.

4. In a spring-motor, two sets of springs formed of flat plates rigidly secured at one

end, in combination with two drums, speed-gearing, and means, substantially as set forth, for putting the said speed-gearing into action by either or both of said drums, substantially as and for the purpose specified.

5. In a motor, a series of straight springs arranged parallel and having their free ends connected together, in combination with a band or chain to transmit power, acted on by all of said springs, substantially as and for the purpose specified.

6. The combination of frame A, springs B B', bands F, drums D D', having spur-wheels C C', speed-gear G, pinions I, J, and K, and levers L and N, substantially as and for the purpose specified.

In testimony of which invention I hereunto set my hand.

BARNES CLAYTON.
